DISPOSABLE FEMININE SYRINGE

James Robert Gross, Bensenville, Ill., assignor to Abbott Laboratories, North Chicago, Ill.

Filed May 14, 1975, Ser. No. 577,255

Term of patent 14 years

Int. Cl. D24—04, 99

U.S. Cl. D83—1 Q

FIG. 1 is a view in side elevation of a disposable feminine syringe showing my new design;

FIG. 2 is a view in side elevation similar to FIG. 1, turned ninety degrees therefrom;

FIG. 3 is a top plan view of the disposable feminine syringe shown in FIG. 2; and

FIG. 4 is a bottom plan view of the disposable feminine syringe shown in FIGS. 1 and 2.

I claim:

The ornamental design for a disposable feminine syringe, substantially as shown and described.
